UNITED STATES PATENT OFFICE

JOSEPH H. THORNTON, OF SPOKANE, WASHINGTON

COMBINATION BOOK HANGER AND ADVERTISING HOLDER

Application filed March 28, 1931. Serial No. 525,957.

My invention relates to combination book hangers and advertising holders and certain objects of the invention are to provide a book hanger made of a single piece of wire 5 that is bent to form a pair of parallel arms for retaining the book in a neat closed position, an offset portion on which a book is suspended through a hole in the book, a finger stop portion disposed below the offset portion 10 and adapted to prevent the book from swinging around, loop portions for hanging the device on a hook or nail and for pivotally swinging same to a position whereby the book may be opened, and a rectangular member connected to one of the parallel arms which serves as an additional means for keeping the book closed and which is adapted for use in holding advertising cards.

With the above and other objects in view 20 which will appear as the description proceeds, the invention consists of the novel construction, adaptation, combination and arrangement of parts hereinafter described and claimed. These objects are accomplished by 25 devices illustrated in the accompanying drawing; wherein:

Figure 1 is a view in perspective showing the general application and installment of the device;

Fig. 2 is a view in vertical section taken substantially on a broken line 2, 2 of Fig. 1;

Fig. 3 is an enlarged detail view in perspective of the complete device;

Fig. 4 is a detail view in transverse vertical section taken on a broken line 4, 4 of Fig. 3; and

Fig. 5 is a fragmentary view in horizontal section taken on a broken line 5, 5 of Fig. 3.

Referring to the drawing throughout which like reference numerals indicate like parts, the numeral 5 designates a straight spring wire arm that is substantially of a length corresponding with the width of a book 6 that is to be suspended by the device, such as a telephone book as shown in Fig. 1. Said arm is bent downward at right angles at 7 and then doubled back upon itself as far as said right angle bend to form a two-ply finger that has a right angle bend at 9 thus

providing a drop portion 10 and a horizontal deflected portion 11.

From the right angle 7 the wire extends upward to form a standing portion 12 whose upper end is fashioned into an annular loop 13. The wire extends at right angles from said loop, as at 14, for a short distance and is then deflected to form a downward reach 15 which reach is deflected to form a short portion 16. Said short portion is of equal length and parallel with the portion 14 and extends to impinge the standing portion 12 thus forming a rectangular loop designated as a whole by the numeral 17. Said rectangular loop and the annular loop 13 are used 55 for suspending the device on a hook or nail and the rectangular loop is particularly used as a finger grasp for moving the entire device to the dotted position shown in Fig. 1 when it is desired to open the book as will 60 be understood.

From the short portion 16 the wire extends downward, as at 18, along the standing portion 12 to a point 19 touching the right angle bend 7. At said point the wire is bent at 75 right angles to form a short offset portion 20 which is of a length slightly greater than the thickness of a book that is to be suspended thereon. From said offset the wire is given another right angle bend to form a reach arm 21 that is parallel with the spring arm 5 and of substantially the same length.

The reach arm 21 is somewhat flattened as shown in cross section in Fig. 4 and its outer face is provided with a plurality of 80 spaced apart notches 22. An advertising holder 23, that may be made of sheet metal, celluloid or the like, is provided at its upper edge with a loop fold 24 which conforms in cross section with the reach arm and is adapted to receive same. Said loop fold is provided with a plurality of indentures 25 disposed in corresponding spaced relation with the notches in the reach arm and adapted to fit into said notches when said holder is 85 installed on said arm for the purpose of retaining same thereon. The lower edge portion of said loop fold is turned up to form a lip 26 and the lower edge of the advertising holder is likewise turned up to provide a lip 90

27, and one or more advertising cards 28 may be slidably installed in said holder with said lips retaining their upper and lower edges as will be understood.

5 To assemble and install the device the advertising holder 23 is removed from the reach arm 21 and said arm is passed all the way through a hole 29 in one corner of the book 6 and the offset portion 20 is moved into said hole. In this position said reach arm and the spring arm 5 will be parallel with the covers of the book on opposite sides thereof and will normally serve to retain the book in a neat closed position thus preventing same from flaring open as is ordinarily the case when no retaining means is provided. The advertising holder is then installed on the reach arm and due to the width and length of said advertising holder same serves as an additional means for keeping the book closed. The device is then suspended on a hook or nail by means of the loop 13 and in the suspended position the horizontal finger portion 11 serves as a stop or shoulder to prevent the book from swinging around or back and forth. To open the book it is merely necessary to pivotally swing the entire hanger to the dotted position shown in Fig. 1 with the finger against the loop 17.

30 Having thus described my invention, it being understood that minor changes may be made therein without departing from its scope and spirit, what I claim and desire to secure by Letters Patent is:

35 1. A combination book hanger and advertising holder comprising a pair of extended arms disposed in parallel spaced relation and adapted to receive a book therebetween, an annular loop and a rectangular loop for the 40 upper portion of the hanger adapted to serve as suspension and finger grasp means respectively, an offset portion transversely disposed at one end of said arms adapted to pivotally support a book by passing same 45 through a hole therein, and a deflected finger portion disposed below said offset portion adapted to engage the rear edge of a book supported by the device whereby same is prevented from swinging about its pivotal support.

50 2. The combination with a book having a hole through one of its back corners of a hanger and advertising holder comprising a pair of extended arms, a transverse offset portion at one end of said arms adapted to retain said arms in parallel spaced relation, one of said arms adapted to be passed through the hole in the book to bring said offset portion into said hole, a deflected finger disposed below said offset and adapted to rest against the back edge of the book in the installed position whereby the book is prevented from pivotal movement, and an annular and 55 a rectangular loop for the upper portion of

the hanger adapted to serve respectively as suspension and finger grasp means.

3. The combination with a book having a hole through one of its corners of a hanger and advertising holder comprising a pair of 60 extended arms adapted to retain the book therebetween, a transverse offset portion at one end of said arms adapted to retain same in parallel spaced relation, one of said arms adapted to be passed through the hole in the book to bring said offset portion into said hole, a deflected finger below said offset adapted to rest against the back of the book whereby the book is prevented from swinging, annular and rectangular loops for the 65 upper portion of the hanger adapted to serve respectively as suspension and finger grasp means, and a rectangular member adapted to be slidably installed on one of said parallel arms and to serve as additional retaining 70 means for the book.

In testimony whereof I affix my signature.
JOSEPH H. THORNTON.
